UNITED STATES PATENT OFFICE

164,388

CYCLE FRAME

Frank W. Schwinn, Chicago, Ill.

Application August 27, 1949, Serial No. 4,721

Term of patent 14 years

(Cl. D90—8)

To all whom it may concern:

Be it known that I, Frank W. Schwinn, a citizen of the United States, residing in Chicago, in the county of Cook and State of Illinois, have invented a new, original, and ornamental Design for a Cycle Frame, of which the following is a specification, reference being had to the accompanying drawings, forming part thereof.

Fig. 1 is a perspective view taken from in front and somewhat to one side of a cycle frame embodying my new design;

Fig. 2 is a side elevational view of the cycle frame depicted in Fig. 1;

Fig. 3 is a front elevational view of the cycle frame shown in Fig. 1;

Fig. 4 is a top plan view of the same;

Fig. 5 is a bottom view of the frame; and
Fig. 6 is a rear elevational view of the illustrated frame.

I claim:

The ornamental design for a cycle frame, substantially as shown.

FRANK W. SCHWINN.
